DESK

John A. Borden, 321 Camino Real W., Apt. 201,
Boca Raton, Fla.

Filed July 28, 1960, Ser. No. 61,556

Term of patent 14 years

(Cl. D33—7)

Fig. 1.

Fig. 2.

Fig. 3.

Fig. 4.

Fig. 5.

The dominant portions of my design are shown in full lines on the drawing.

I claim:

The ornamental design for a desk, as shown and described.
